HENRY WEBER, OF CHICAGO, ILLINOIS, ASSIGNOR TO LATHAM MACHINERY COMPANY,
OF CHICAGO, ILLINOIS, A CORPORATION OF ILLINOIS.

FEEDING MECHANISM.

1,192,481.

Specification of Letters Patent. Patented July 25, 1916.

Application filed March 13, 1914. Serial No. 824,393.

To all whom it may concern:

Be it known that I, HENRY WEBER, a citizen of the United States, residing at Chicago, in the county of Cook and State of Illinois, have invented certain new and useful Improvements in Feeding Mechanism, of which the following is a specification.

My invention relates to feeding mechanism and has for its primary object the provision of improved feeding mechanism which shall have means whereby one wire may be fed at regular intervals, and a second wire fed at any predetermined intervals.

With the above and other objects in view this invention consists substantially in the combination, arrangement, and construction of parts all as hereinafter described, shown in the accompanying drawings which form a part of this specification and illustrate the preferred embodiment of my invention, and more particularly set forth in the subjoined claims.

In the drawings: Figure 1 is a side elevation of a device embodying my invention, illustrating in conjunction therewith a holder and wire reels supported thereby. Fig. 2 is a detailed view of the device shown in Fig. 1 and illustrates in dotted lines a position which the parts assume in operation. Fig. 3 is a section taken approximately on line 3—3 of Fig. 2. Fig. 4 is a section taken approximately on line 4—4 of Fig. 2. Fig. 5 is a section taken approximately on line 5—5 of Fig. 2. Fig. 6 is a partial section taken approximately on line 6—6 of Fig. 2. Fig. 7 is a section taken on line 7—7 of Fig. 5. Fig. 8 is a perspective view of a ratchet and disk illustrated in Figs. 1, 2, 4, and 5. Fig. 9 is a plan view of a piece of work stapled by the device illustrated in the figures and embodying my invention.

Reference numeral 10 indicates generally a stapling head of any suitable construction and embodying a frame plate 11, a cammed wheel 12, a feeding lever 13, a feeding frame 14, a cutter 15, a former 16, a hammer 17, an anvil 18, a supporter 19, and a supporter block 20. The type of stapling head illustrated in the drawings is one well known in the prior art, and in it the cammed wheel 12 operates the feeding frame 14 by contact with the feeding lever 13, the feeding lever reciprocating the feed-

ing frame upon two guide rods 21; the cammed wheel 12 also reciprocates the cutter 15, the former 16, the hammer 17, and the anvil 18, the supporter 19 being operated by contact with the hammer. In Fig. 60 1 there is illustrated a reel holder 22 carrying reels 23 and 24 which deliver wires 25 and 26 respectively to the stapling head 10. Retrograde movement of the wires 25 and 26 is prevented by means of any suitable 65 holding device, generally indicated by reference numeral 27. The path of movement of the feeding frame 14, which path may be varied by rotation of a handle 28, is illustrated by means of dotted lines in Fig. 2. 70 This feeding frame carries two feeding clutches 29 and 30, which normally engage the wires 25 and 26 respectively during the forward or feeding movement of the frame 14 and feed the wires to the cutting, forming, and driving mechanism. Upon the backward movement of the feeding frame 14, that is, from the position shown in dotted lines in Fig. 2 to that shown in full lines, 75 the clutches 29 and 30 slip over the wires 80 25 and 26 without moving them.

In the present embodiment of my invention it is illustrated in combination with a stapling head such as described above, and it includes means for idling the wire clutch 85 30 during a predetermined interval such, for example, as that illustrated in Fig. 9 wherein, after the setting of the two staples illustrated at the left end of the line of staples in the work, the clutch 30 was idled during 90 an interval sufficient to allow the clutch 29 to feed seven staples; in other words, my invention provides means whereby in conjunction with a single line of staples an extra staple may be fed to the setting mechanism at intervals predetermined by the operator. In Fig. 9 the work operated upon is indicated by reference numeral 31 and in it, in the adjustment of parts illustrated in the drawings, the apparatus has set staples 100 nine times, beginning with setting two staples, 32 and 33, then setting seven single staples 32, and upon the ninth operation, setting again two staples 32 and 33, the staples 32 being fed from the wire 25, and 105 the staples 33 from the wire 26. The present invention is of great utility in that it provides means for double stapling the ends of a seam. To accomplish the idling of the clutch 30 I form thereon an extension 110 34

and in suitable relation to the extension 1 provided upon the feeding frame 14 a pivot pin 35, upon which is mounted for rotation a disk 36, provided upon its outer face with a ratchet 37 having in the present adjustment of parts nine ratchet points 38: the disk 36 and ratchet 37 are fixed with respect to each other and both rotatable about the pivot pin 35. The disk carries upon its peripheral surface the extension 34 and normally prevents the clutch 30 from engaging the wire 26. The disk is provided with any suitable number of notches, the present adjustment of parts necessitating the use of two such notches 39 and 40. Whenever, during the rotation of the disk, the extension 34 engages one of the notches in the disk the succeeding forward or feeding movement of the feeding frame 14 will feed not only the wire 25 but also the wire 26, for the reason that the descent of the extension 34 into the notch of the disk permits the clutch 30 to act upon the wire 26 to feed it. The mechanism illustrated in the drawings is adjusted to set staples in groups of nine settings and in every group to set nine single staples and two extra staples. The number of extra staples set by the machine will, however, in all cases be controlled by the number of notches provided in the periphery of the disk 36, the extra staples being formed from the wire 26.

To accomplish the rotation of the disk 36 a dog 41 is provided which, as the feeding frame 14 moves forward to the dotted position shown in Fig. 2, engages one of the ratchet points 38 and turns the ratchet and disk partially about the pivot pin 35. To accomplish the complete rotation of the disk 36, as many engagements between the ratchet 37 and the dog 41 are necessary as there are ratchet points 38 upon the ratchet. A slide bar 42 is mounted for horizontal movement within the block 20, the movement being accomplished by means of a pivot 43, an eccentric 44 mounted for oscillation upon the pivot and engaging an aperture 45 provided in the bar 42. As is shown in Fig. 5 the dog 41 is pivoted as at 46 upon one end of the bar 42. The cam 44 is provided with an extension 47 which carries a pointer 48 and is provided with a handled set screw 49. In an arc having the pivot 43 for a center is provided a series of apertures 50 in the block 20 for engagement with the set screw 49 and suitable graduations 51 corresponding to the apertures 50 are provided upon the outer face of the block 20, the graduations in the present embodiment of the invention being numbered from 5 to 9 and indicating in each instance the number of ratchet points 38 upon the particular disk 36 which the operator has set upon the pivot pin 35. In the present adjustment of parts there are nine ratchet points illustrated

upon the ratchet 37, and in consequence thereof the cam 44 has been moved until the pointer 48 registers with the graduation 9, and the set screw 49 has been placed in engagement with the hole 50 which corresponds to the graduation 9. This setting of the cam 44 positions the slide bar 42 at the extreme inner end of its path of movement and properly positions the dog 41 for engagement with the ratchet 37 when the ratchet has, as is illustrated in Figs. 2 and 8, nine points. If a lesser number of points is desired upon the ratchet, for instance five, the cam 44 is oscillated to move the dog toward the feeding frame 14. The position which the extension 47 then assumes is illustrated in dotted lines in Fig. 1, wherein it is seen that the pointer 48 registers with the graduation 5 upon the block 20. This adjustment of the dog 41 is necessary, in order that it may produce a greater angular movement at each reciprocation of the feeding mechanism corresponding to the greater arc covered by each tooth on the ratchet 37. Upon the former 16 (see Fig. 7) are provided an upper stud 52 and a lower stud 53, these studs engaging an extension 54 upon the dog 41 and oscillating the dog during the time that it engages the ratchet 37 to cause it to positively turn the ratchet; during the downward movement of the former the stud 52 engages the extension 54 and oscillates the dog upwardly to turn the ratchet, and during the upward movement of the former the stud 53 engages the extension 54 and returns the dog to the position shown in dotted lines in Fig. 2.

Considering the parts to be positioned as illustrated in full lines in Fig. 2, the operation of the present invention is as follows: The extension 34 has dropped into the notch 39, allowing the clutch 30 to grip the wire 26. The clutch 29 also grips the wire 25 and contact between the cammed wheel 12, and the feeding lever 13 moves the weeding frame 14 and the clutches 29 and 30 forward into the position shown in dotted lines. This motion feeds sufficient wire to form two staples. As the feeding frame 14 completes its forward stroke the dog 41 engages a notch of the ratchet 37, following which the former 15 descends to form staples, causing the upper stud 52 to engage the extension 54 of the dog and throw the dog upward into contact with one of the ratchet points 38. This upward movement of the dog turns the ratchet 37 and disk 36 through one-ninth of a circle and causes the extension 34 to rise from the notch 39 to the periphery of the disk 36, this latter movement arresting any gripping effect of the clutch 30 upon the wire 26. The feeding frame 14 reciprocates to the position shown in full lines in Fig. 2, and the rise of the former brings the lower stud 53 into contact with extension 130

54 and returns dog 41 to the position illustrated in dotted lines in Fig. 2. At the next oscillation of the feeding lever 13 the feeding frame 14 is a second time carried forward to the dotted position shown in Fig. 2, but at this second forward movement no action is had with respect to the wire 26, for the reason that the clutch 30 is rendered inoperative for the time being. The wire 10 25, is, however, fed forward singly to the cutter seven times following the first described feed of both wires and at each single feed of the wire 25 the dog 41 turns the disk 36 through one-ninth of a circle. Upon the 15 eighth forward movement of the feeding frame 14, however, the notch 40 is presented to the extension 34, which descends into it so that when the feeding frame is returned into the full line position it will, upon its 20 ninth forward movement, feed forward both wires 25 and 26. Following each forward movement of the feeding frame 14 the cutter, former, hammer, and anvil have performed their functions, each being constructed to handle two wires instead of one, and staples 32 and 33 have been set into the piece of work 31 in the manner illustrated in Fig. 9. Obviously, as many notches as desired may be provided in the disk 36, and 25 as each notch comes into proper position it will be engaged by the extension 34, causing at the next forward movement of the feeding frame 14, a feed of both wires to the cutter. In the manufacture of articles such as straw-board boxes, it is frequently necessary to double staple the ends of the seam of the box, binding the seam between the ends by single staples. It will readily be seen that 30 by positioning the notches 39 and 40 approximately one-ninth of a circle apart the seam in the work 31, which requires stapling at nine points, will, if the stapling is begun when the extension 34 is in engagement with the notch 39, be double stapled at its ends, 35 or at its first and ninth staple points, and single stapled therebetween. It has been said that the seam in the work 31 requires staples at nine points. This is, of course, an arbitrary requirement of commerce, but, 40 should it be desired to staple it at five points, for instance, instead of nine, and to double staple the end points of the seam, a disk 36 would be provided and a ratchet 37 thereupon, having five ratchet points 38 instead 45 of nine, and the notches 39 and 40, instead of being approximately one-ninth of a circle apart would be approximately one-fifth of a circle apart. From this explanation it will be understood what was meant above 50 by setting staples in groups of nine settings and it will be readily understood, also, that while a disk of any size may be used having any suitable number of ratchet points for a given kind of work, my feeding mechanism may be run continuously in a seam 55

and caused to set extra staples at any desired intervals along that seam, regardless of the number of points in the seam to be stapled.

In the accompanying drawings and in the 70 foregoing description is set forth the preferred embodiment of my invention, but it is obvious that one skilled in the art may make modifications thereof without departing 75 from the spirit of the invention.

I claim:

1. The combination of a reciprocating clutch adapted to draw wire in one direction, and mechanism whereby said clutch may be rendered inoperative and automatically rendered operative after a predetermined number of reciprocations. 80

2. The combination of a reciprocating clutch adapted to draw wire in one direction, and mechanism whereby said clutch 85 may automatically be rendered inoperative during a predetermined number of reciprocations.

3. The combination with apparatus for drawing wire in one direction, of mechanism for rendering the apparatus inoperative during predetermined intervals, comprising a rotatable notched disk engaging the apparatus to remove it from the wire, 90 said apparatus engaging the periphery of the disk when removed from the wire and engaging the notches of the disk when in contact with the wire. 95

4. The combination of a reciprocating device for drawing wire in one direction, an extension upon said device, a disk engaging said extension to withhold the device from contact with the wire and notched for engagement with the device to allow the device to grip the wire, and means for rotating 100 the disk. 105

5. The combination of a clutch operable to draw wire in one direction, means for reciprocating the clutch, an extension upon the clutch, a rotatable disk adapted to render the clutch inoperative when the extension rides upon the periphery of the disk, 110 and notched to drop the extension from said periphery and render the clutch operative, and means for rotating the disk step by 115 step.

6. The combination of a reciprocating clutch operable to draw wire in one direction, a rotatable disk notched in its periphery and adapted to raise the clutch on its periphery to render the clutch inoperative, 120 said clutch engaging the notches of the disk to lower the clutch and render it operative, and means for rotating the disk step by 125 step.

7. The combination of a reciprocating clutch operable to draw wire in one direction, a rotatable disk notched in its periphery and adapted to raise the clutch on its periphery and render the clutch inopera- 130

5 tive, said clutch engaging the notches of the disk to lower the clutch and render it operative, and means for rotating the disk step by step, comprising a ratchet fixed with respect to the disk and concentric therewith, said disk and ratchet being reciprocated with the clutch, and a dog lying in the path of reciprocation of the ratchet.

10 8. The combination of a reciprocating clutch operable to draw wire in one direction, a rotatable disk notched in its periphery and adapted to raise the clutch on its periphery to render the clutch inoperative, said clutch engaging the notches of the disk 15 to lower the clutch and render it operative, and means for rotating the disk step by step, comprising a ratchet fixed with respect to the disk and concentric therewith, said disk and ratchet being reciprocated with the 20 clutch, and a pivoted dog lying in the path of reciprocation of the ratchet.

25 9. The combination of a reciprocating clutch, operable to draw wire in one direction, a rotatable disk notched in its periphery and adapted to raise the clutch on its periphery to render the clutch inoperative, said clutch engaging the notches of the disk 30 to lower the clutch and render it operative, and means for rotating the disk step by step, comprising a ratchet concentric with the disk and fixed thereto, a pivoted dog interposed in the path of movement of the ratchet, and means for oscillating the dog upon its pivot, said ratchet and disk being 35 reciprocated with the clutch.

40 10. The combination with a reciprocating clutch for feeding one wire periodically, of a reciprocating clutch for feeding another wire at predetermined intervals differing 45 from the intervals between the feeding operations of the first said wire, and means actuated by the movement of said last named clutch for controlling the intervals of feeding said second wire.

50 11. The combination with a reciprocating clutch for feeding one wire periodically a given number of times, of a reciprocating clutch for feeding another wire simultaneously with the first and last feeds of the first wire but permitting said second wire to remain inactive during the intermediate feeds of the first wire, and means carried by said second reciprocating clutch for controlling the intervals of feeding of said second wire.

55 12. The combination with an oscillating wire feeding clutch member, of mechanism carried by said clutch member for feeding wire at mechanically predetermined intervals regulated by the number of oscillations 60 of said clutch member, the intervals between the oscillations of the clutch member and the intervals between the feedings of the wire being different from one another.

65 13. The combination with an oscillating wire feeding clutch member, of mechanism

carried thereby for automatically feeding one wire periodically and another wire at different predetermined intervals, and means controlled by the oscillations of said clutch member for determining the intervals of 70 feeding of said last mentioned wire.

14. The combination with suitable mechanism having a former and a reciprocating feeding frame, of a pivoted dog, means carried by the former for oscillating the dog, a feeding clutch for one wire carried by the feeding frame and operable at each reciprocation thereof to feed wire, a second wire clutch carried by the feeding frame, an extension upon the second clutch, a disk rotatably mounted upon the feeding frame, adapted to carry the extension upon its periphery to render the second wire clutch inoperative, and notched for engagement with the extension to render the second wire 85 clutch operative, and means carried by the feeding frame and contacting with the dog to rotate the disk step by step.

15. The combination with suitable mechanism having a former and a reciprocating feeding frame, of a pivoted dog, means carried by the former for oscillating the dog, a feeding clutch for one wire carried by the feeding frame and operable at each reciprocation thereof to feed wire, a second 90 wire clutch carried by the feeding frame, an extension upon the second clutch, a disk rotatably mounted upon the feeding frame, adapted to carry the extension upon its periphery to render the second wire clutch inoperative, and notched for engagement with the extension to render the second wire 95 clutch operative, and a ratchet concentric with the disk, fixed thereto, and mounted upon the feeding frame to engage the dog 100 at each reciprocation of the feeding frame.

16. The combination with stapling mechanism having a former and a reciprocating feeding frame, of a pivoted dog, means carried by the former for oscillating the dog, a 110 feeding clutch for one wire, carried by the feeding frame and operable at each reciprocation thereof to feed wire, a second wire clutch carried by the feeding frame, an extension upon the second clutch, a disk rotatably mounted upon the feeding frame adapted to carry the extension upon its periphery to render the second wire clutch inoperative, and notched for engagement with the extension to render the second wire 115 clutch operative, and a ratchet concentric with the disk, fixed thereto, and mounted upon the feeding frame to engage the dog at each reciprocation of the feeding frame, said former oscillating the dog during its 120 engagement with the ratchet wheel.

17. The combination of an oscillatory wire grip for feeding the wire a given number of times, and a second oscillatory wire grip for automatically feeding a second wire 130

simultaneously with the first and last feeds of the first wire, said second grip remaining inoperative to feed the wire during intermediate feeding of the first wire.

5 18. In combination, a multiple wire feed including a reciprocating wire grip for feeding one wire at regular intervals, and a second reciprocating wire grip for automatically feeding another wire simultaneously with the feed of the first named grip and at predetermined intervals differing from the intervals at which the first said grip operates.

10 19. A movable apparatus for feeding wire, comprising means for gripping a wire to be fed, and means for periodically and automatically rendering said gripping means alternately operative and inoperative to grip

the wire while said feeding apparatus continues its movement. 20

20. A movable apparatus for feeding wire, comprising means for gripping a wire to be fed, and automatic means operable at predetermined intervals for rendering said gripping means inoperative to grip the wire 25 while said feeding apparatus continues its movement.

In testimony whereof I have signed my name to this specification, in the presence of two subscribing witnesses, on this 10th day 30 of March, A. D. 1914.

HENRY WEBER.
